UNITED STATES PATENT OFFICE.

EVA KELLER, OF PASADENA, CALIFORNIA.

PIANO PRACTICE EXERCISER.

Application filed October 27, 1925. Serial No. 65,118.

My invention is designated as a piano practice exerciser and stabilizer, adapted to facilitate the learning of the proper control and manipulation of the arm, including the upper arm and forearm, the wrist, hand and fingers in playing the piano.

An object of my invention is to provide appliances which may be attached to the hand, wrist and arm, such appliances being adapted to facilitate a student learning the proper motion and control for the arm, wrist, hand and fingers.

One of the difficulties in learning to play the piano is to acquire what is designated as the free and loose elbow by which the player learns to maintain the elbow in a free or flexible condition without any rigid clamping. Also the wrist motion must be free to allow easy bending up and down and sideways. The knuckles must also be held in the proper position in order to have the fingers engage the keys in the approved manner to give the best touch when playing the piano.

To accomplish these ends I utilize a series of appliances which may be utilized all at the same time or separately according to the particular exercises being practiced or particular parts of musical compositions for which the student is endeavoring to acquire the proper technique.

These appliances are in the form of weights some of which are rigidly clamped in relation to the hand, arm or wrist, others of which have a swinging or oscillating motion.

To acquire the proper position for the knuckles I secure a weight to the back of the hand over the knuckles this weight being graduated so that more pressure is brought to bear on the knuckles of the first and second fingers than on the knuckles of the middle finger. This weight is kept in position by a band over the palm of the hand and by a pair of flexible straps attached to the wrist.

To acquire the flexible wrist motion I attach a swinging weight by a spring strip metal to the wrist, the weight depending below the wrist so that the swinging of the weight will teach the pupil the free and flexible wrist motion.

To teach the flexible or loose elbow motion I secure a band over the forearm at approximately the position of the elbow and suspend the weight at the lower end of the

band. This weight preferable has a rolling ball to give a sound indication of the proper rhythmic oscillation of the weight.

I also provide an arm piece attached to the wrist and to the forearm adjacent the elbow. This arm piece comprises a tube suspended below the forearm and having a certain amount of mercury contained therein so that the mercury can shift in position in accordance with the raising and lowering of the wrist relative to the elbow. I also provide an adjustable and slideable weight on the exterior of the tube to load the arm at any particular position.

My invention in its various aspects will be more readily understood from the following description and drawings, in which;

Fig. 1 is a plan view of the assembled appliances in the position they would occupy when all are utilized at the same time.

Fig. 2 is a side elevation of Fig. 1 in the direction of the arrow 2.

Fig. 3 is a vertical transverse section on the line 3—3 of Fig. 1 or 2, illustrating the construction of the hand weight.

Fig. 4 is a vertical section on the line 4—4 of Fig. 2, in the direction of the arrow, illustrating the oscillating weight of the elbow piece, showing the rolling ball mounted therein.

Fig. 5 is a vertical transverse section on the line 5—5 of Fig. 2, looking in the direction of the arrows, showing the wrist piece with the oscillating weight.

Fig. 6 is a vertical section on the line 6—6, indicating the attachment of the arm piece to the wrist.

Fig. 7 is a diagrammatic illustration of my exerciser and stabilizer attached to the forearm, wrist and hand when all are being used at the same time.

Fig. 8 is a detail of a glove-like device with weights on the finger portions at about the position of the second joint.

Referring particularly to Figs. 1 and 2, the hand weight is designated by the numeral 1, being connected to a wrist band 2, adapted to retain the weight in the proper position in relation to the wrist. The arm piece 3 is secured to the wrist band at its outer end and the inner end is secured to a forearm band 4 adapted to be positioned on the arm slightly forward of the elbow. The oscillating weight elbow piece 5 is connected to the forearm band 4 to maintain it in proper position and the weighted wrist piece 6 is se-

cured to the wrist band to hold it in adjusted position and is shown as of a resilient construction.

The use of these various elements in assembly will be apparent after their individual construction and purpose is understood.

The hand weight 1 is illustrated particularly in Figs. 1, 2 and 3 and comprises a body 10 of considerable weight, being preferably made of lead. This body is thicker over the inside portion 11 which is intended to be substantially over the knuckles of the first and second finger, than the outer portion 12 which is adapted to fit over the knuckles of the little finger and the third finger, as it is usually more difficult for the pianist to maintain the knuckles of the first and second fingers in proper relation to the knuckles of the third and little fingers.

A resilient spring clip 13, preferably formed of spring steel is engaged to the body 10 preferably by casting the end 14 into the lead and the inner end 15 of the clip is intended to press upwardly in the palm of the hand on the inner side of the knuckles. The outer side of the weight has a flexible metal strip 16 which preferably has one end 17 cast in the body of the lead. This strip is intended to be bendable and of such character that it will retain the curvature to which it is bent. Some brass alloys or soft iron are suitable for this purpose. A flexible strap 18 is connected by a rivet or the like to the free end 19 of the strip 16 and another strap 20 is secured to the end 15 of the spring clip 13. These two straps are adjustably connected by a series of dome fasteners 21. If desired these straps may be formed of elastic material to allow stretching and resiliency in playing the piano.

A pair of preferably metal back bands 22 and 23 are secured to the body of the weight, preferably by casting in the lead and their free ends are connected to the wrist band 2. This connection is preferably by a dome fastener 24 on the wrist band, being adapted to engage one of a series of apertures 25 on the back bands. This allows a certain adjustment to accommodate the position of the weight to hands of different lengths.

A plurality of dome fasteners 26 are formed on the wrist band so that this band may be fitted to different size wrists or made loose or tight.

As above mentioned the weight 10 is heavier over the knuckles of the first and second fingers than over those of the third and little finger, as most piano pupils elevate their first and second knuckles too high in reference to the knuckles of the third and little fingers. Moreover, the weight teaches the pupil the proper pressure to bring on the keys from the ends of the fingers and enables them to acquire a firm but light touch of the keyboard.

The arm piece 3, which is illustrated particularly in Figs. 1, 2 and 6 comprises a wrist band 2 which has a depending web 27 secured to the wrist band by dome fasteners 27' formed with an eye 28 therein. The forearm 70 band 4 has a series of dome fasteners 29 allowing it to be fitted to arms of different sizes to bind tightly thereon, and a web 30 depends from the lower end of the band, being secured by dome fasteners 30', having an eye 31 75 at the lower end of the web. These webs and eyes are preferably made of fabric webbing, although they may be made of elastic material or leather as may also the wrist and the forearm bands. 80

The arm piece proper, designated by the numeral 3, comprises a tube 32 adapted to fit in the eyes 28 and 31 forming a snug fit and being retained by friction. This tube is closed at one end 33 and at the other end has a closure cap 34 indicated as being screw threaded in the end of the tube. A certain amount of mercury 35 is placed in the tube before the cap is closed, but not sufficient to fill the tube as it is my intention that the mercury will flow freely from one end of the tube to the other or backwards and forwards in accordance with the relative elevation of the wrist and the elbow. 90

An adjustable weight 36 is mounted on the outside of the tube and by means of a small set screw 37 may be clamped in any desired position, thus giving a heavy stationary weight adjacent the elbow or the wrist or at any intermediate point. If it is desired in certain practicing to emphasize the shifting weight, a greater or a less quantity of mercury may be placed in the tube and the set screw 36 may be loosened so that the weight 36 will freely slide on the outside of the tube. 100

The elbow piece 5 is shown in particular in Figs. 1, 2 and 4 and comprises a band 38 preferably of metal adapted to fit freely over the forearm adjacent the elbow. This band is kept in proper relation to the elbow by a strap 39 rigidly secured to the forearm band, this latter having a metal plate 40 and the strap being connected thereto by a series of dome fasteners 41. The band 38 is 115 also adjustably secured to the strap 39 by means of a series of dome fasteners 42.

The oscillating weight 43 is formed by securing a cap 44 to the lower end of the band, preferably by means of a bolt 45 having the end 46 inside the cap and the nut 47 at the lower portion of the band. This allows the cap and the band to be tightly secured together to position the weight with its long axis in substantially the same plane as the band 38 or at right angles or other angular position therewith. A shell 48 forms the base of the weight and is preferably connected to the cap by a screw threaded connection 49. A tray 50 120

is inserted in the shell 48 and preferably has a pressed fit so that it may be readily inserted and removed.

A ball 51 is adapted to roll on the floor 52 of the tray and to strike against the ends 53. An adjustable filling 54 is placed in the shell preferably by pouring molten lead therein in the desired quantity to give the weight required. This lead may then be 10 added to or cut out as desired.

The manner of using the elbow piece is substantially as follows:

The elbow piece is mounted in the manner above described and when the student practices exercises on the piano at the same time swinging the arm slightly until the weight oscillates in the proper rhythm, the clicking of the ball indicates the proper rhythm. Moreover, the fact of the weight swinging 20 forces the student to have a free and loose elbow motion.

The weighted wrist piece 6 is constructed substantially as follows, being shown particularly in Figs. 1, 2 and 5:

25 A flexible wrist metal strip 55 has an inwardly curved end 56 adapted by its own resiliency to press inwardly against the wrist, the portion 57 resting on the upper part of the wrist. A depending section 58 is bowed outwardly a sufficient distance to clear the tube 32 and has a stem end 59 with a series of apertures 60 therethrough, whereby a ball 61 having a hole 62 therethrough may be attached to the stem by a cotter pin 63 or similar fastening. The wrist metal strip is secured to the wrist band by means of a strip 64, the latter being secured to the wrist band 2 by a series of dome fastenings 65 and preferably having a dome fastening 66 engaging in one of a series of perforations 67, in the metal strip, allowing adjustment of the weight and the strip in various position longitudinally and angularly of the wrist.

40 It is to be understood that the piano student will have a set of my piano practice exerciser and stabilizer of a size to suit the arms and hand of the student. The hand weight 1 may be adjusted to fit different hands by filing some of the lead off or hammering it to the proper shape. The various other elements of the whole device may also be adjusted to different size hands, wrists and arms. The adjustable features are intended to be fully complete so that if necessary the various appliances may be adjusted to suit different students whereby the same set may be utilized by a large number of pupils.

45 It is apparent that when specific exercises are being undertaken that the different elements above described can be used separately. For instance the hand weight may be used without any of the other appliances by disconnecting the web 27 and thus the

complete arm piece. Also the arm piece may be utilized by itself by disconnecting the hand weight and by disconnecting the elbow and wrist pieces. Also if desired the elbow piece can be utilized alone either by loosely swinging it over the arm or by having the upper portion secured to the upper arm band 4; the web 30 being disconnectible from the band. The wrist piece 6 may also be utilized separately by passing the metal 70 strip 55 over the wrist with or without attaching this to the wrist band 2.

75 It will thus be seen that the various elements of my exerciser and stabilizer may be used together or separately and that 80 when utilized together they will have their specific functions all tending to develop certain features of control in the technique of piano playing.

85 It is obvious that the different elements embodied in my invention may be changed considerably in their general construction and specific details and that the assemblage of these may also be altered to suit different requirements in learning and maintaining 90 the piano technique. These changes may be made without departing from the spirit of my invention as set forth in the description, drawings and claims.

95 The finger weighting device is indicated generally by the numeral 70 and is illustrated in part in Fig. 1 and in Fig. 8. This comprises a glove-like structure 71 having the finger portions cut off at about the second joint as indicated by the numeral 72 and having straps 73 with dome fasteners 74 to engage with fasteners 75 on the hand weight 1. The glove is preferably made of woven material and has stitched therein a series of weights 76, these being positioned 100 as close to the second joint of the finger as convenient. The thumb portion 77 is connected to the glove-like structure by a webbing 78. This device places weights which 105 may be changed to suit different pupils on the fingers and materially aids the exercising of the fingers, giving them increased strength as well as teaching the proper pressure to bear on the keyboard.

110 Having described my invention, what I claim is:

1. A piano practice exerciser comprising in combination a hand weight to be attached to the back of a person's hand, an arm piece having means to secure same to a person's forearm, an elbow oscillating weight suspended from the forearm, adjacent the elbow and a weighted wrist piece adapted to engage the wrist, having a resilient strip with a weight depending below the wrist.

120 2. A piano practice exerciser as claimed in claim 1, having a wrist band operatively connected to the hand weight, means to support the arm piece at one end from the wrist band, a forearm band to support the other 130

- end of the arm piece, a connecting strap between the forearm band and the elbow oscillating weight and a strap connected to the wrist band and the wrist piece.
5. 3. A piano practice exerciser comprising in combination a hand weight to rest on the back of a person's hand over the knuckles, means passing under the palm of the hand from the weight, a wrist band clamped 10 around the wrist, back bands connecting the weight to the wrist band, a forearm band, eyes depending from the wrist band and from the forearm band, a tubular arm piece supported in said eyes and having 15 a movable weight therein, an elbow oscillating weight having a band fitting loosely over the forearm with a weight depending therefrom, means to connect the forearm band and the band of the elbow 20 weight, a wrist piece having a flexible strip with a weight at the lower end, the strip being adapted to engage a person's wrist and means to connect the strip over the wrist piece to the wrist band.
25. 4. A piano practice exerciser as claimed in claim 3, in which the elbow oscillating weight has a movable element therein to cause a sound on the oscillation of the weight.
30. 5. In a piano practice exerciser, a hand weight comprising a structure having a body extending across the back of a person's hand, the structure being of lesser dimensions lengthwise of the hand than crosswise thereof, having an underneath shape adapted to conform somewhat to the back of a person's hand at the knuckles, and means passing under the palm of the hand to attach the weight to the hand.
35. 6. In a piano practice exerciser as claimed in claim 5, in which the weight is of greater thickness at the part to fit over the knuckles of the first and second finger than that to fit over the fourth finger, and having a spring 40 clip connected to one end of the body, said clip being bent to engage underneath the palm of the hand, the clip forming part of the means passing under the palm of the hand to attach the weight to the hand.
45. 7. In a piano practice exerciser, a hand weight having a body structure extending across the back of the hand, of greater dimensions across the hand than lengthwise thereof, the body structure being thicker at the part to fit adjacent the knuckles of the first and second fingers than at the part to fit adjacent the knuckle of the fourth finger, the body structure being shaped to fit the back of the hand adjacent the knuckles, a 50 spring clip secured to one end of the body and bent to engage the inside of the palm of the hand, and a flexible strip secured to the other end of the body adapted to engage over the other side of the hand and partly under the palm.
8. In a piano practice exerciser as claimed in claim 7, having in addition a wrist band to engage a person's wrist and back bands connecting the body of the weight to the wrist band. 70
9. In a piano practice exerciser, an arm piece comprising in combination a wrist band and a forearm band, to be secured to the wrist and forearm, a tubular member secured to the said bands and a movable weight in said tubular member. 75
10. In a piano practice exerciser as claimed in claim 9, in which the wrist bands are provided with webs, said webs having eyes forming supporting elements for the tube. 80
11. In a piano practice exerciser as claimed in claim 9, having in addition a 85 slideable weight mounted on the outside of the tube.
12. In a piano practice exerciser, an elbow oscillating weight comprising a band to extend over a person's forearm, a weight secured to the end of the band and means in the weight to cause a sound on oscillation of the band. 90
13. In a piano practice exerciser, an elbow oscillating weight comprising a band of stiff material to fit over a person's forearm, a weight attached to the lower end of the band, a ball mounted in the weight, a runway in the weight for the ball, said ball causing a sound on the oscillation of the weight. 95
14. In a piano practice exerciser as claimed in claim 13, in which the weight is adjustably mounted on the band. 100
15. In a piano practice exerciser as claimed in claim 13, in which the runway is removable to allow the addition or removal of material to add or decrease the amount of the weight. 105
16. In a piano practice exerciser, a wrist piece comprising a resilient strip, said strip being bent at its upper ends to engage a person's wrist and having a weight depending from the lower end. 110
17. In a piano practice exerciser as claimed in claim 16, in which the weight is adjustable on the strip. 115
18. A piano practice exerciser comprising in combination a hand weight to be secured to the back of a person's hand, a wrist band, a forearm band, an elbow oscillating weight, a wrist piece having a weight, an arm piece suspended from the wrist and the forearm band, and means to detachably secure the weight to the wrist band, the arm piece to the wrist and the forearm bands, the elbow weight to the forearm band and the wrist piece to the wrist band. 120
19. A piano practice exerciser comprising in combination a finger weighting device having partial glove fingers with weights attached to said finger elements, a hand 125
- 130

weight, means to attach the finger weighting device to the hand weight, an arm piece operatively connected to the hand weight and an oscillating weight elbow piece operatively connected to the arm piece.

20. In a piano practice exerciser, a finger weighting device having a glove-like structure with the ends of the fingers removed,

to fit over part of the fingers, weights in the ends of the finger portions and straps to secure the glove-like structure to a device to fit around a person's hand.

In testimony whereof I have signed my name to this specification.

EVA KELLER.
